UNITED STATES PATENT OFFICE.

GEORGE H. THOMPSON AND JOHN CURRIE, OF SEATTLE, WASHINGTON.

SCREW PROPELLER.

1,418,991.

Specification of Letters Patent. Patented June 6, 1922.

Application filed December 28, 1920. Serial No. 433,572.

To all whom it may concern:

Be it known that we, GEORGE H. THOMPSON, a subject of the King of England and JOHN CURRIE, a citizen of the United States, 5 residing at Seattle, in the county of King and State of Washington, have invented certain new and useful Improvements in Screw Propellers, of which the following is a specification.

10 This invention relates to screw propellers for marine vessels.

The object of our invention is, generally, to provide a device of this character whereby power may be utilized more fully than 15 hitherto for driving a vessel.

A specific object of the invention is to provide a propeller having blades of large areas arranged to produce a minimum of drag and which operate with an absence of 20 churning.

The invention consists of a propeller having a plurality of bifurcated blades of peculiar form which are disposed in spiral or helical relations.

25 The invention further consists in the novel construction, adaptation and combination of parts as will be hereinafter described and claimed.

In the accompanying drawings, Figure 30 1 is an end elevation of a propeller embodying our invention. Fig. 2 is a side elevation of the same, and showing the relative arrangement of the blades. Figs. 3, 4, and 5 are sectional views through 3--3, 4--4, 35 and 5--5 of Fig. 1.

In said drawings, the numeral 10 designates the propeller hub provided with a plurality of bifurcated blades, denoted by A, B, C, which are disposed spirally about 40 the hub for revolutions in different planes. Each of said blades comprises a shank element 11 and two fluke elements 12 and 13.

45 Said shank and flukes are formed to be approximately helical in sections taken concentric of the propeller axis. As shown in Fig. 4, the flukes are of substantially plano-convex forms in transverse sections, the convex face being forward in the leading fluke and to the rear in the following fluke of a 50 blade. The leading fluke 12 is curved forwardly from the shank to the tip thereof and the other fluke 13 is curved rearwardly as best represented in Fig. 3, while the outer

edges 14 of the complementary flukes are coextensive to afford a configuration of an 55 elongated letter S in the end view of a blade as shown, for example, with respect to the blade C in Fig. 2.

By thus curving the flukes of a blade in reverse directions there is afforded at the 60 periphery of the propeller a passage, as 65 Fig. 4, between complementary flukes whereby the water may travel in an unbroken state from in front of the leading fluke 12 to the rear of the following fluke 13.

Similar to the flukes, the blades themselves 70 are disposed in such relations with respect to each other to provide therebetween passages circumferentially of the propeller.

By forming both the blades and the flukes 75 thereof in helical relations they offer little resistance when revolving through the water but provide a maximum driving force to propel a vessel.

The curving of the blades in the respective 80 flukes from the region of their divergence to the fluke tips serves to reduce the centrifugal movement of the water without breaking the same.

By arranging the blades and their flukes 85 as described the propeller also acts efficiently when its motion is reversed to retard, stop or back the vessel to which it is applied.

What we claim, is,—

A propeller comprising a hub and a series 85 of bifurcated blades disposed in helical relations with respect to each other about the hub, the bifurcation or fluke elements of said blades being broad and of substantially 90 plano-convex form in transverse section with the convex sides of the complementary flukes at the front and rear sides respectively, the 95 complementary flukes of a blade being curved to have the tips and outer side portions thereof respectively directed forwardly and rearwardly or toward each other and with the outer edges of each pair of flukes coextensive and in the similitude of an elongated letter S.

Signed at Seattle, Washington, this 13th 100 day of December 1920.

GEORGE H. THOMPSON.
JOHN CURRIE.
